UNITED STATES PATENT OFFICE.

CHARLES GOOGE AND HENRY LINDSEY, OF CORINTH, MISSISSIPPI.

SAFETY DEVICE FOR RAILROAD SWITCHES.

Application filed March 12, 1926. Serial No. 94,254.

This invention relates to a safety device. It more particularly relates to a safety device for railroad switches.

An object of the invention is to provide means for locking the switch points of a railroad switch in place.

Another object is to provide a safety device for railroad switches which is readily installed on the usual switch and which is inexpensive to manufacture.

Other objects and advantages will herein after appear.

An embodiment of the invention is illustrated in the accompanying drawing, of which:

Figure 1 is a top plan view of a railroad switch with the safety device installed thereon;

Figure 2 is a vertical sectional view taken on line 2—2 of Figure 1;

Figure 3 is a sectional view taken on line 3—3 of Figure 1;

Figure 4 is a top plan view of the cam actuator.

Figure 5 illustrates an end elevational view of a switch showing the operating rods in assembled relationship therein.

The safety device may be installed on any existing form of switch and is adapted to operate independently of the switch. The main line of a railroad is indicated at 1, while a siding 2 is shown as being adapted to be connected therewith by means of a switch.

The switch is constructed in the usual manner and has customary switch ties 3, bridle rod 4 and switch stand 5. It is understood, of course, that the rails are secured to the ties in any preferred and usual manner and that any conventional form of switch may be used.

The safety device proper comprises a bar of iron or other material 6 having the center thereof formed with an offset portion 7. This bar or strap fastens to the ties on each end and is so arranged that the offset portion 7 comes under the bridle rod 4. The bar is adapted to lie along side of the rail. Superimposed upon the bar 6 is a bar 8 but not provided with an offset portion. The bars 6 and 8 are each provided with aligned openings located slightly inwardly of the switch ties 3. The bar 8 also is provided with an opening at its central portion, the purpose of which will be later explained.

A bar 9 of shorter length than the bars

6 and 8 is superimposed thereon but is spaced therefrom by the nuts or washers 10 and 11. The central part of this bar has an opening corresponding to and in alignment with the opening in the bar 8.

A headed pin 12 is adapted to pass through the openings in the bars 9 and 8 and also through an opening in the bridle rod 4.

Arranged above the bar 9 is a bar 13. The bars 9 and 13 are provided with openings corresponding to the openings in the bars 6 and 8 above mentioned. Through the right hand set of these openings a bolt 14 is passed while through the left hand set of openings a slideable bolt 15 is passed. The bolts 14 and 15 also pass through the nuts or washers 10 and 11.

An L-shaped rod 16 has the short end 17 thereof extending vertically through the bars adjacent to the bolt 15 and has the end of the long arm thereof connected to the bolt 14. A coil spring 18 is arranged between the end of the long arm of the member 16 and the bottom of the bar 6.

From the foregoing description, it will be apparent that if the pin 15 is raised, that the bar 9 will be elevated because of the nut 10 and that the pin 12 will likewise be raised out of engagement with the opening in the bridle rod 4. When the pin 15 is allowed to fall downwardly to its original position, the spring 18 will tend to return all the parts to their normal relation. A resilient member 18 may be located in operative relationship with the portion 17 of the device, if so desired, to aid the spring 18 in returning the switch elements to normal position. In order to provide an easy and efficient means for elevating the pin 15, a cam 19 is movably connected with the tie so as to engage the bottom end of the pin. This cam is connected by a link 20 to a substantially U-shaped operating rod 21 which is adapted to be rotated in bearings 22 and 23.

It will thus be seen that when the switch has been thrown and the pin 12 engaged in the opening in the bridle rod 4, that it will be impossible, though the switch stand 5 is knocked down, to throw the switch until the pin 12 is again withdrawn from the bridle rod.

In connection with the operation of the device, it may be stated that bolts 14 and 15 are adapted to carry ground nut elements 10 and 11, and the diameters of the bolts

are much less than the openings in which they operate. The bolts 14 and 15 are made smaller in diameter for the reason that they can then operate in all the bars 5 freely and may be tilted from either end, which functions to raise the lock pin 12 easily out of the bridle rod 4. The coil spring 18 is fastened on the bolt 14 extending underneath the bridle rod and over the top 10 of the upper plate for the reason that it has a tendency to pull down on that end of the bar which will function to return the pin 12 into interlocked relationship with the bridle bar 4. Obviously, by making the 15 bolts much smaller than the openings through the bars in which they operate, the device functions to operate freely. That is, the single cam element 19 functions, according to this invention, to lift the bar 9 near 20 one end thereof and at the same time the other end of the bar 9 will also be allowed to rise owing to the fact that the shank of bolt 14 is of smaller diameter than the opening through which it extends in bar 9. 25 The cam element 19 may be made from any suitable material, such as an iron bar, and formed having a portion adapted to contact with raising pin 15 when desired. The cam is preferably provided with an opening for 30 receiving the link 20 and there is also another opening in the cam through which it may be pivotally connected to a switch tie. Obviously, when the link element 20 is pulled, a portion of the cam comes in contact with and lifts the pin 15, thereby functioning to raise the locking pin 12 from the 35 bridle rod 4.

The invention is susceptible of various modifications and adaptations within the 40 scope of the appended claims.

Having thus fully described our invention, we claim:

1. A safety device for railroad switches comprising a slidable shielded pin adapted

to engage an opening in the switch bridle 45 rod, means for moving said pin into engagement with said opening, and means for moving said pin out of engagement with said opening.

2. A safety device for railroad switches 50 comprising a slidable pin adapted to engage an opening in the switch bridle rod, means for automatically moving said pin into engagement with said opening in a predetermined position of the bridle rod, and means 55 operating independently of the switch for moving said pin out of engagement with said opening to allow the switch to be operated.

3. The combination with a railroad switch 60 and the bridle rod therefor, of a safety device comprising a slidable pin adapted to engage an opening in said bridle rod, means for automatically moving said pin into engagement with said opening in a predetermined 65 position of the bridle rod, and cam means operating independently of the operation of the switch for moving said pin out of engagement with said opening to allow said switch to be operated. 70

4. The combination with a railroad switch and the bridle rod therefor, of a safety device comprising a slidable pin adapted to engage an opening in said bridle rod, means for automatically moving said pin into engagement with said opening in a predetermined 75 position of the bridle rod to retain said switch and bridle rod in locked position, cam means operating independently of the operation of the switch for moving said 80 pin out of engagement with said opening to allow said switch to be operated, and means for moving said cam means. 70

In testimony whereof they affix their signatures.

CHARLES GOOGE.
HENRY LINDSEY.
